UNITED STATES PATENT OFFICE

ARTHUR VON FRANKENBERG, OF NEW YORK, N. Y.

DESIGN FOR A LAMP OR SIMILAR ARTICLE

Application filed July 8, 1930. Serial No. 36,299. Term of patent 3½ years.

To all whom it may concern:

Be it known that ARTHUR VON FRANKENBERG, a citizen of the United States, and resident of New York city, in the county of New York and State of New York, has invented a new, original, and ornamental Design for a Lamp or Similar Article, of which the following is a specification, reference being had to the accompanying drawing, forming part thereof, in which the figure is a perspective view of a lamp embodying my new design, the side of the lamp opposite that shown in the drawing being substantially the same as the portion of the lamp between the two rear figures shown in the drawing.

I claim:

The ornamental design for a lamp or similar article, substantially as shown and described.

Dated, July 2, 1930.
